WASHING MACHINE

Glen G. Blandford, Grand Rapids, Mich.

Application January 10, 1936, Serial No. 58,442

4 Claims. (Cl. 259—101)

The present invention relates to washing machines and the like; and its object is to provide a very stable construction of such a machine; and further, to provide such a machine whose parts may be relatively moved to positions wherein the same may be readily cleaned and obstructions removed.

These and any other and more specific objects hereinafter appearing are attained by, and the invention finds preferable embodiment in, the machine particularly described in this specification and illustrated by the accompanying drawing, in which:—

Figure 1 is an elevational view of a washing machine showing its parts in operative position;

Figure 2 is a sectional view of the lower portion thereof taken on a diametrical vertical plane corresponding to line 2—2 of Figure 3;

Figure 3 is a sectional view of operative parts of the machine taken on a diametrical vertical plane corresponding to line 3—3 of Figure 1; and

Figure 4 is a sectional view of said parts taken on the same plane but showing these parts in inoperative position and the dasher or "dolly" raised.

In this drawing a washing machine is shown having a cylindrical container 1 with an open top provided with a removable cover 2, and adapted to receive the goods to be washed and water for washing the same. The flat bottom 3 of this container is supported by a base member or spider 4 having angularly spaced radial arms 5 terminating in downwardly extending legs 6. The bottom portion of the container fits, desirably removably, in an annular band 7 creased or bent inwardly to form a strengthening rib 8 engaging the bottom portion of the container, and having downwardly extending parts 9 which, as shown, may be separate parts secured as by rivets 10, these parts 9 being bent inwardly over or around the legs 6 as particularly well shown in Figure 2, whereby a stable and rigid connection of the band 7 and the base 4 is provided. The foregoing parts are desirably made of sheet metal, except the base member 4 and its integral arms 5 and legs 6 which are desirably a metal casting.

The dasher or "dolly" 11 is tightly secured to the upper end of the vertical rock shaft 12 inside the container, and as shown has the horizontal base portion 13 and a suitable number—three in the shown construction—of radial wing portions 14. This shaft 12 extends downwardly through the bottom 3 of the container and rotatably bears at 15 in the nut 16 threaded through said bottom.

The shaft has the tight bevel gear 17 at its lower end, this gear having a journal portion 18 rotatable in a bearing 19 in the horizontal portion 20 of the downwardly extending arm 21 of the base casting 4.

The dolly or dasher is rocked back and forth by a horizontal rock shaft 22 turnable in a bearing 23 in the base member's arm 21 and a bearing 34 extending through one of the legs 6 and through the part 9 which embraces said leg as shown in Figure 2. This shaft has an operating crank handle 24 at its outer end and at its inner end has a bevel gear 25 meshing with the gear 17. The gear 25 is interrupted at 26 so that when the shaft 22 is turned to the position seen in Figure 4, the gears 17, 25 are moved out of mesh by sliding the vertical shaft 12 upwardly in its bearing 15 far enough to raise the dolly to the position seen in Figure 4 so that the same and the bottom of the container beneath it may be thoroughly cleaned and any obstruction between the dolly and the bottom may be readily removed.

A member 29 surrounding the shaft 12 is shown threaded in the nut 16 with a packing between them as shown in Figure 2 to prevent leakage from the container. Rubber feet 30 surrounding the legs of the machine are desirably provided as shown.

It is evident that this machine is adapted for other uses than as a washing machine, such as for churns and the like.

The bevel gear 17 has its smaller diameter-side upwardly as shown so that the meshing engagement of the bevel gear 25 tends to hold the dasher down in the container.

The invention being intended to be pointed out in the claims, is not to be limited to or by details of construction and arrangement of the particular embodiment thereof illustrated by the drawing or hereinbefore described.

I claim:

1. In a machine of the class described: a container element; a rigid supporting element therefor having downwardly tapering legs; an element for connecting the container element and the supporting element together connected to the container element and having parts bent over the legs respectively in tightly embracing relation therewith for permanently joining the supporting element and the connecting element together.
2. In a machine of the class described: a container element; a rigid supporting element therefor having angularly spaced leg portions; an element for connecting the container element and the supporting element together comprising a

band part embracing the container element and downwardly extending sheet metal parts bent over the leg portions respectively in tightly embracing relation therewith for permanently joining the supporting element and the connecting element together.

3. In a machine of the class described: a container element; a cast metal supporting element therefor having radial arms on which the container element rests, said arms having downwardly tapering leg portions; a sheet metal element for connecting the container and the supporting elements together comprising a band part embracing the container element and downwardly extending parts bent over the leg portions respectively in tightly embracing relation there-

with for permanently joining the supporting element and the connecting element together.

4. In a machine of the class described: a container element; a cast metal supporting element therefor having radial arms on which the container element rests, said arms having leg portions; a sheet metal element for connecting the container and the supporting elements together comprising a band part embracing the container element and downwardly extending parts bent over the leg portions respectively in tightly embracing relation therewith, the band part having an annular inwardly extending rib in supporting engagement with the periphery of the container element's bottom.

15 GLEN G. BLANDFORD.
